ROLLER SCREEN AND ATTACHMENT FOR
WINDOWSJoseph Pontuck and Samuel Finkelstein,
Brooklyn, N. Y.

Application September 28, 1939, Serial No. 296,880

8 Claims. (Cl. 156—39)

This invention relates to new and useful improvements in a roller screen and attachment for windows.

More specifically, the invention proposes the construction of a roller screen which may be used in conjunction with the windows of an automobile, airplanes, railway cars, houses, sky-lights, porches, screen doors and similar objects having slide windows.

Still further it is proposed to characterize the roller screen by a housing attached upon a window sill and having a screen extendable therefrom across a window opening.

A further object of this invention is to provide binding strips extending along said screen and beyond the free edges thereof and to provide an auxiliary screen extending between the free edge of said screen and the end of said strips for closing the remaining portion of said opening when desired.

Another object of this invention is to provide a roller rotatively adjustably mounted across the binding strips and to attach one end of the auxiliary screen thereto and to provide means for holding the auxiliary screen in its extended positions.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an outside elevational view of a window having a roller screen constructed according to this invention.

Fig. 2 is an enlarged sectional view taken on the line 2—2 of Fig. 1.

Fig. 3 is a view similar to Fig. 2 showing the inner construction of the housing.

Fig. 4 is a sectional view on the line 4—4 of Fig. 3.

Fig. 5 is a sectional view on the line 5—5 of Fig. 1.

Fig. 6 is a sectional view on the line 6—6 of Fig. 1.

Fig. 7 is a view looking in the direction of the line 7—7 of Fig. 6.

Fig. 8 is an enlarged sectional view on the line 8—8 of Fig. 1.

Fig. 9 is an inside elevational view of twin windows having a roll screen construction according to a modification of this invention.

Fig. 10 is a vertical sectional view substantially on the line 10—10 of Fig. 9.

Fig. 11 is a vertical sectional view similar to Fig. 10, but illustrating a still further modification of the invention.

The roller screen and attachment for windows, according to this invention, comprises a housing 10 for attachment upon a window sill 11 of a window 12. The window 12 is of conventional construction having window sashes 12^a and 12^b slidably supported in a window frame in the customary manner. The housing 10 is constructed from sheet metal or other material and is fixedly attached upon the window sill 11 by means of lugs 13. A cover 10^a is provided for closing the open top of the housing 10.

A spring roller 14 is mounted within the housing 10 for rolling a screen upon itself. The roller 14 is formed at one of its ends with a peg 15 rotatively supported in the said end and extending from the end of a circular housing 16 mounted over the said end. The peg 15 is formed at its outer end with a square portion 15^a which engages a complementary square opening formed in a bracket 17 attached to one end wall of the housing 10. The cooperation between the square end 15^a and the square opening formed in the brackets 17 limits the peg against rotating. A means is provided for causing the roller 14 to always return to its normal position after having been turned out of said normal position.

The returning means comprises a spring 18 co-axially engaged upon the peg 15 and having one of its ends engaging an opening 20 formed in the end of the roller 14 and the other of its ends engaging an opening 21 formed in the peg 15. This spring 18 is confined within the tubular housing 16 and is adapted to be tightened upon the peg 15 when the roller is rotated in one direction for returning the roller 14 to its normal position when the said roller is released.

A screen 22 has one of its ends securely attached to the roller 14. The screen 22 is of a width to extend entirely across the opening in the window frame when the sash 12^b is moved upwards. Binding strips 23 are mounted along the edges of screen 22 and have their free ends extending past the free end of the screen 22. The strips 23 are securely attached to the screen 22 by means of rivets 24 which extend through portions of the strips 23 and the screen 22. The strips 23 are constructed from leather or similar material and are of channel shape and have the edges of the screen 22 engaged between the adjacent arms thereof.

A member 25 is securely attached to the free ends of the strips 23. This member 25 comprises

a piece of channel shaped metal having the free ends of the strips 23 engaged between the arms thereof and securely attached thereto by means of rivets 26. A means is provided for attaching 5 the member 25 to the window sash 12^b and comprises bolts 27 engaging through the member 25 and threadedly engageable with nuts 28 securely attached to the bottom edge of the window sash 12^b. When this member 25 is securely attached 10 to the window sash 12^b and the window sash is raised as shown in Fig. 1, the screen 22 will be extended from the housing 10 against the action of the spring 18.

A roller 29 for an auxiliary section of screen 15 is rotatively adjustably mounted between the binding strips and the top edge of the screen portion 22. The strips 23 in the vicinity of the top edge of the screen 22 are formed with enlarged portions 23^a into which the ends of the roller 29 engage. These enlarged portions 23^a are clearly 20 shown in Fig. 2, 3, 6 and 7. The means for rotatively adjustably supporting the roller 29 comprises a headed pin 30 engaging through an opening 31 formed on one of the strips 23 and 25 engaging into one end of the roller 29. At the other end the roller 29 is formed with a square peg 32 which extends through a square opening 33 formed in the other strip 23, and the portion of the square peg 32 which extends beyond the 30 outer edge of the strip 23 is formed with an opening. A cotter pin 34 is adapted to be passed through the opening, and have its free ends bent apart for preventing accidental disengagement of the cotter pin and for holding the square peg 35 in position within the opening.

A means is provided for permitting the square peg to be easily disengaged from the square opening when the cotter pin 34 is removed therefrom for purposes of rotating the roller 29. This 40 means comprises elongated slots 35 formed in the enlarged portion 23^a of the strip 23 through which the square peg 32 extends so that the portion between these slots may be bent out of the plane of the remaining portion of the strip 45 23 to disengage the square opening from the square peg. In their separated positions it is possible for the roller 29 to be manually rotated.

An auxiliary section of screen 36 has one of its ends wound upon the roller and extendable 50 upwards from the free edge of the screen 22 to the member 25. This auxiliary screen 36 is also the same width as the width of the opening in the window frame and has its edges slidably engaging the strips 23.

55 A resilient means is connected with the top edge of the auxiliary screen 36 and is connected with the member 25 for holding this auxiliary screen in its extended positions. This latter means comprises tubular members 37 having their upper ends closed and their bottom ends aligned with openings 38 formed in the top face of the strips 25. Springs 39 have one of their ends securely attached to the upper end of the housing 37 and the other of their ends secured 60 to a U-shaped member 40 attached to the free end of the auxiliary screen 36. Rivets 41 extend through the adjacent face of the auxiliary screen 36 and the U-shaped member 40 for holding this member in fixed position thereon. This auxiliary screen 36 is normally adapted to close the opening between the free edge of the screen 22 and the bottom edge of the member 25. When desired, the free edge of the auxiliary screen 36 may be adjusted to various positions along 70 the opening between the screen 22 and the mem-

ber 25 for providing a small space between the top edge of the auxiliary screen 36 and the member 25 which is not closed by screening. One adjusted position of the auxiliary screen is shown in Fig. 1.

When the window sash 12^b is moved into its lowered position illustrated by the dot and dash lines 12' in Fig. 2, the member 25 will move to the position illustrated by the dot and dash lines 25' in Fig. 2 to enclose the screen 22 and the auxiliary screen 36 within the housing 10. The cover 10^a is formed with an opening 10^{aa} of a sufficient width to permit the enlarged portions 23^a to pass therethrough so as to be wound upon the roller 14.

15 The operation of this device is as follows:

The housing 10 is secured upon the window sill 11 and the member 25 is secured to the bottom edge of the bottom sash 12^b by engaging the bolts 27 therethrough and threadedly engaging them on the nuts 28 fastened to the bottom edge of the sash 12^b. The screen 22 may now be extended from the opening 10^{aa} formed on the cover 10^a by moving the sash 12^b upwards. This causes the screen 22 and the strips 23 to be unwound from the roller 14 against the action of the spring 18. When the desired position for the sash 12^b had been reached the open portion extending between the top edge of the screen 22 and the bottom of the member 25 may be closed 30 if desired by extending the auxiliary screen 36.

To extend the auxiliary screen 36 one must remove the cotter pin 34 from the opening formed in the extended end of the square peg 32. Then one's finger nails are engaged into 35 the slots 35 and that portion of the strip 23 which is located between the slots 35 is bent out of the plane of the remaining portion of this strip to disengage the square opening 33 from the square peg 32. Then the roller 29 is 40 free to be rotated in a direction to unwind the auxiliary screen 36 therefrom to permit the springs 39 to move the said screen upwards. When a sufficient portion of the opening has 45 been closed the square peg is again engaged into the square opening and the cotter pin 32 applied thereto for holding these parts in their interengaged relationship. The cooperation between the square peg and the square opening prevents the roller 29 from being rotated by the springs 50 39.

According to the modification shown in Figs. 9 and 10, the construction of the roll screen is similar of that previously described except that the construction is shown applied to the inside 55 of a twin window 12'. A hollow casing 10' is mounted upon the window sill 11' and has two separate and distinct roll screens mounted therein each of which is individually attached to the bottom sash of each window of the twin window 60 12'. Likewise there is a hollow casing 10'' attached to the top of the window frame. This housing 10'' is also provided with two separate and distinct roll screen constructions each of which is attached to the top edge of one of the 65 top sashes of said twin window. In other respects this form is identical to the prior form and the same parts may be recognized by the same reference numerals.

According to the modification shown in Fig. 11, 70 the construction of the roll screen is similar to that previously described except the hollow casing 10''' is mounted below the window sill 11''''. A similar screen casing 10''' is mounted above the top of the window frame and is provided with 75

suitable doors 10^a. The screens 22' are mounted to the window sashes 12^a and 12^b in any suitable manner.

It is to be understood that this screen device 5 may be used for any suitable purpose and at any desired location.

While we have illustrated and described the preferred embodiments of our invention, it is to be understood that we do not limit ourselves 10 to the precise constructions herein disclosed and the right is reserved to all changes and modifications coming within the scope of the invention as defined in the appended claims.

Having thus described our invention, what we 15 claim as new, and desire to secure by United States Letters Patent is:

1. In a roller screen, a spring operated self winding screen for attachment on a window frame and having a free end, strips mounted on 20 the side edges of said screen and projected beyond the free end thereof, means attaching the free ends of said strips to the bottom edge of an open window sash forming an unscreened area between the bottom edge of said sash and the 25 free end of said screen, a roller mounted between said binding strips adjacent the free end of said screen, and an auxiliary screen having one end wound upon said second roller and adapted to be extended upwards to the bottom edge 30 of said window sash for closing said unscreened area, whereby when said window sash is moved to a closed position said spring operated self-winding screen will wind up the screen portion thereof and also wind up said strips and said auxiliary screen.

2. In a roller screen, a spring operated self winding screen for attachment on a window frame and having a free end, strips mounted on the side edges of said screen and projected beyond the free end thereof, means attaching the free ends of said strips to the bottom edge of an open window sash forming an unscreened area between the bottom edge of said sash and the free end of said screen, a roller mounted between 40 said binding strips adjacent the free end of said screen, and an auxiliary screen having one end wound upon said second roller and adapted to be extended upwards to the bottom edge of said window sash for closing said unscreened area, 45 whereby when said window sash is moved to a closed position said spring operated self-winding screen will wind up the screen portion thereof and also wind up said strips and said auxiliary screen, said means comprising a longitudinal 50 member releasably attached to said window sash and having the free ends of said strips attached to the ends thereof.

3. In a roller screen, a spring operated self winding screen for attachment on a window frame and having a free end, strips mounted on the side edges of said screen and projected beyond the free end thereof, means attaching the free ends of said strips to the bottom edge of an open window sash forming an unscreened area 55 between the bottom edge of said sash and the free end of said screen, a roller mounted between said binding strips adjacent the free end of said screen, and an auxiliary screen having one end wound upon said second roller and adapted to be extended upwards to the bottom edge of said 60 window sash for closing said unscreened area, whereby when said window sash is moved to a closed position said spring operated self-winding screen will wind up the screen portion thereof and also wind up said strips and said auxiliary 65 screen, and means for releasably non-rotatively supporting said second roller.

4. In a roller screen, a spring operated self winding screen for attachment on a window frame and having a free end, strips mounted on the side edges of said screen and projected beyond the free end thereof, means attaching the free ends of said strips to the bottom edge of an open window sash forming an unscreened area 70 between the bottom edge of said sash and the free end of said screen, a roller mounted between said binding strips adjacent the free end of said screen, and an auxiliary screen having one end wound upon said second roller, comprising a pin having an enlarged head extending from one end of said second roller and rotatively extended through one of said strips, a square peg extend-

ing from the other end of said second roller and passing through a square opening formed in the other of said strips, and means for holding said square peg against becoming accidentally disengaged from said square opening.

7. In a roller screen, a spring operated self winding screen for attachment on a window frame and having a free end, strips mounted on the side edges of said screen and projected beyond the free end thereof, means attaching the free ends of said strips to the bottom edge of an open window sash forming an unscreened area between the bottom edge of said sash and the free end of said screen, a roller mounted between said binding strips adjacent the free end of said screen, and an auxiliary screen having one end wound upon said second roller and adapted to be extended upwards to the bottom edge of said window sash for closing said unscreened area, whereby when said window sash is moved to a closed position said spring operated self-winding screen will wind up the screen portion thereof and also wind up said strips and said auxiliary screen, and means for releasably non-rotatively supporting said second roller, comprising a pin having an enlarged head extending from one end of said second roller and rotatively extended through one of said strips, a square peg extending from the other end of said second roller and passing through a square opening formed in the other of said strips, and means for holding said square peg against becoming accidentally disengaged from said square opening, and said strip being formed with slots on either side of said square opening which permits the portion of said strip located between said slots to be bent out of the plane of the remaining portion of said strip to permit said square peg to be disengaged

from said square opening so that said second roller may be manually rotated for extending and retracting said auxiliary screen.

8. In a roller screen, a spring operated self winding screen for attachment on a window frame and having a free end, strips mounted on the side edges of said screen and projected beyond the free end thereof, means attaching the free ends of said strips to the bottom edge of an open window sash forming an unscreened area between the bottom edge of said sash and the free end of said screen, a roller mounted between said binding strips adjacent the free end of said screen, and an auxiliary screen having one end wound upon said second roller and adapted to be extended upwards to the bottom edge of said window sash for closing said unscreened area, whereby when said window sash is moved to a closed position said spring operated self-winding screen will wind up the screen portion thereof and also wind up said strips and said auxiliary screen, said means comprising a longitudinal member releasably attached to said window sash and having the free ends of said strips attached to the ends thereof, and resilient means on said member urging said auxiliary screen into position across said unscreened area, comprising a tubular housing for each end of said auxiliary screen mounted on top of said member, said housings having their top ends closed and their bottom ends aligned with openings formed in said member, and springs having one of their ends attached to the free edge of said auxiliary screen and the other of their ends attached to the closed end of said tubular housing for normally extending said auxiliary screen.

JOSEPH PONTUCK.
SAMUEL FINKELSTEIN.
